UNITED STATES PATENT OFFICE

132,381

DESIGN FOR A WIRE TWISTING DEVICE

Wilfred E. Tabb, Cleveland Heights, and William Paul, South Euclid, Ohio, assignors to Jack & Heintz, Inc., Bedford, Ohio

Application March 5, 1942, Serial No. 106,026

Term of patent 14 years

To all whom it may concern:

Be it known that we, Wilfred E. Tabb and William Paul, citizens of the United States and residents of Cleveland Heights, county of Cuyahoga, State of Ohio, and South Euclid, county of Cuyahoga, State of Ohio, respectively, have invented a new, original, and ornamental Design for a Wire Twisting Device, of which the following is a specification, reference being had to the accompanying drawing, forming part thereof.

Figure 1 is a side elevational view of a wire twisting device showing our new design;

Figure 2 is a top plan view thereof; and
Figure 3 is an end elevational view thereof.

We claim:

The ornamental design for a wire twisting device, substantially as shown.

WILFRED E. TABB.
WILLIAM PAUL.
